CASING HEAD

Laurence L. Rector, Fort Worth, Tex.

Application December 9, 1935, Serial No. 53,603

5 Claims. (Cl. 166—15)

This invention relates to new and useful improvements in casing heads.

This application is filed as a continuation in part of my co-pending application Serial Number 671,819 filed May 19, 1933.

One object of the invention is to provide an improved casing head having means for carrying a blowout preventer, or other safety device, whereby the casing may be run through said device and head without danger of the casing being blown from the well.

An important object of the invention is to provide an upwardly extending screw-threaded nipple at the upper end of the casing head, said nipple being either made integral with the head or constructed separately and arranged to be connected to the base of the head in place of the retaining cap and gland thereof, whereby a suitable safety device through which the casing may be run is had.

Still another object of the invention is to provide an improved flanged adapter which may have any desired inner diameter and which may be bolted to the base of a casing head, whereby a suitable safety device may be mounted thereon, said adapter being arranged to permit easy insertion of the split sealing and supporting ring to support the casing after said casing has been run into the well.

A further object of the invention is to provide an improved method of running tubing into a cased well having a casing head which includes, mounting a safety device above said head, running said tubing through said safety device and head, landing the tubing in the casing head, removing the safety device, and then closing the casing head.

A still further object of the invention is to provide an improved method of running tubing through a casing head which consists in, running said tubing through a safety device and head while retaining the well pressure, then supporting the casing in the head and sealing off said head, and then removing the safety device, whereby the well pressure is controlled throughout the operation.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is an elevation of a casing head, to which an adapter, constructed in accordance with the invention, may be applied.

Figure 2 is a transverse, vertical sectional view of the same.

Figure 3 is a view, partly in elevation and

partly in section and showing an adapter, constructed in accordance with the invention, mounted on the base member of the casing head, and also showing a gate valve and blowout preventer mounted above the casing head, with the inner casing being run into the well.

Figure 4 is a view similar to Figure 3 and showing the supporting ring inserted on the base member of the casing head.

Figure 4a is a vertical, sectional view of the flanged adapter.

Figure 5 is a view showing a modified form of the adapter.

Figure 6 is an isometric view of the split ring.

Figure 7 is a transverse, vertical, sectional view of the casing head having an adapter made integral with its upper end, and

Figure 8 is a view similar to Figure 7, and showing the cap and adapter raised from the base member of the casing head to permit the insertion or removal of the supporting ring.

In the drawings, the numeral 10 designates a cylindrical body which forms the base member of the casing head. This body is provided with a reduced lower end 11 which is externally screw-threaded, whereby said body may be screwed into the upper end of the outer, or surface casing of the well, or other support (not shown).

An annular outwardly extending flange 12 is formed integral with the upper end of the body, and below said flange diametrically opposite threaded openings 13 are provided. These openings receive the ends of outlet pipe 14 whereby fluid from within the body may be carried outwardly through said pipe. A split sealing and supporting ring 15 is arranged to seat on the upper end of the base member 10, as is clearly shown in Figure 2. This supporting ring is constructed of any suitable metal and its underside which engages the upper end of the base member is ground, whereby leakage of pressure thereby is prevented. The split ring has its inner periphery engaging in a groove 16 formed centrally of an elongated double collar 17, whereby said ring serves to support said collar axially within the base member. The inner casing A is, of course, threaded into the collar, whereby said casing is suspended therefrom. A flanged cap 18 fits over the upper end of the ring and has its flange 19 secured to the flange 12 of the base member 10 by suitable bolts 20 and nuts 21. Annular packing rings 22 are interposed between the flanges of the cap and the body.

The cap 18 has an annular internal shoulder 23 at its upper end and a suitable packing ring 24 is seated thereon. A packing gland 25 has its lower end engaging the packing ring 24 to hold the same in place, and said gland is secured to the cap 18 by stud bolts 26 which extend upwardly from said cap. Nuts 27 screwed on the upper

end of said stud bolts serve to apply the required pressure to the gland and packing ring 24.

This structure, which has just been described, is a casing head such as is disclosed in my Patent No. 1,834,968, issued December 8, 1931, and the various parts which have been so described are merely for purposes of clarity and the particular structure forms no part of the present invention other than as a means for carrying out

10 the improved method which will be hereinafter described.

In carrying out the invention, a flanged adapter 30 is provided. This flange is clearly shown in Figure 4a and includes an annular base flange 15 31 with an externally screw-threaded, tapered nipple 32 extending upwardly therefrom. The flange has a plurality of openings 33 therein and these openings are arranged to register with the openings in the annular flange 12 of the base member 10 when said flange is placed upon the base member. The bore 34 of the adapter is enlarged at its lower end, whereby an internal annular shoulder 35 is formed.

In carrying out my improved method, the base member 10 of the casing head is screwed into the upper end of the outer casing or surface pipe B (Figure 3). The cap 18 together with the packing gland 25 is then removed from the base member 10 by loosening the bolts 20 and nuts 21. The 25 split ring 15 is also removed. The adapter 30 is then positioned on the flange 12 of the base member 10 and the bolts 20 and nuts 21 are again tightened to fasten the adapter to said base member. The parts are then in the position shown in Figure 3 with the screw-threaded nipple of the adapter extending upwardly from the base member of the casing head. The annular packing rings 22 which are interposed between the flange 12 and the flange 31 will, of course, prevent a 30 leakage of pressure through the space between these flanges. A suitable gate valve C is then screwed onto the nipple 32 of the adapter 30. A blowout preventer D is then mounted above the valve in the usual manner and thus, it will be seen that by providing the adapter it is possible to secure the gate valve and blowout preventer above the casing head. It is pointed out that at this time the inner casing has not been run into the well, the only casing being the outer or surface casing.

Heretofore, it has been the usual practice to run both the outer and inner casing before securing the safety devices, such as the blowout preventer and gate valve above the casing head. 55 It has been found that by waiting until the casing has been run into the well, there is no way of holding the well pressure and as a result this pressure is not only wasted but also causes a fire hazard as well as creating danger of a blowout. 60 Therefore, it is desirable that the well be held under control during the running of this inner casing.

After the blowout preventer and gate valve have been mounted as hereinbefore described, the inner casing or tubing A is then lowered through the preventer D, the gate valve C, and through the casing head base member 10 into the outer or surface casing B. During this lowering operation, the rams E of the blowout preventer will 65 prevent the escape of gas or other well pressure upwardly around the inner casing A which is being lowered, and will cause the gas, mud, water or other fluid within the hole and travelling upwardly through the outer casing B to escape 70 through the outlet pipes 14 provided for this pur-

pose in the base member 10 of the casing head. This will prevent the gas and other pressure from blowing the inner casing from the well during the lowering operation, and also will eliminate all danger of fire hazard or other disadvantages. 5 It is noted that with the split ring 15 removed from the casing head, there is no obstruction to the lowering of the inner casing A and a smooth operation is assured.

When the double collar 17, which is screwed onto the upper end of the casing A has been lowered to a height opposite the annular flange 31 of the adapter, the nuts 20 and bolts 21 are removed, and the adapter 30, together with the valve C and blowout preventer D, are raised, as clearly shown 15 in Figure 4. The split ring 15 is then quickly placed in position on top of the base member 10 and the preventer, valve and adapter are again lowered and fastened in position. The enlarged portion of the bore 34 of the adapter 30 20 engages around the split ring 15 when in position, and serves to retain said ring in place. The inner periphery of said ring, of course, engages in the groove 16 of the double collar whereby the inner casing A is suspended within the hole. 25

After the split ring 15 has been positioned within the casing head, it is obvious that the ground joint seat will positively prevent the escape of well pressure thereby. Therefore, if it is desired to remove the blowout preventer and gate valve the 30 adapter 30 may be entirely removed together with said preventer and valve. With such removal the pressure will be under control because the weight of the string A is holding the split ring 15 on its seat to prevent leakage of the well pressure. The cap 18 and packing gland 25 of the 35 casing head may then be substituted for the adapter 30 in which case, the casing head will, from this point on, function in its usual manner. It is, of course, obvious that if it is desired to 40 run another string of inner casing, it is only necessary to screw the lower end of another casing head, smaller in size, into the upper end of the double collar 17. In such case, an adapter would be provided for the base member of this smaller 45 casing head and the running of another string would be accomplished in the same way.

With the method herein described, it will be seen that during the entire lowering operation of the inner casing, the gas, oil or well pressure 50 is completely under control. Before the running operation is commenced, the blowout preventer and gate valve are mounted thereabove to positively shut in the well. The inner casing is run through the blowout preventer and the rams of this preventer positively prevent escape 55 of well pressure. After the inner casing has been landed or moved to its proper position, it is only necessary to loosen the bolts 20 and nuts 21 to permit the preventer and gate valve together 60 with the adapter, to be raised sufficiently to permit insertion of the split ring 15, whereby the inner casing is suspended in the hole. It is then possible either to replace the adapter, valve and preventer or to remove these parts and attach the usual cap and packing gland of the casing head.

By keeping the gas or well pressure under control throughout the entire running of the inner casing, all danger of a blowout of the inner casing caused by such pressure or a fire due to the 70 sparks igniting leaking gas is eliminated. If the adapter 30 were not provided, the well would be wide open while the inner casing A is being run, and this is one of the disadvantages which the 75

method herein described overcomes. It is to be clearly understood that the invention is not to be limited to a gate valve or a blowout preventer mounted above the adapter 30, but any suitable safety device may be mounted thereon. In some cases, it might be desirable to assemble the split ring and double collar before the same is lowered into the adapter 30. In other words, it has been found that in some cases it is best to place the split ring 15 within the groove 16 of the double collar before said collar is lowered within the adapter 30. In such case, the adapter 30 could not be employed because of its reduced bore 34. To permit the assembled ring and collar to be lowered into position, another form of adapter 40 is provided. This adapter is similar to the adapter 30 and is arranged to be attached to the annular flange 12 of the base member 10 of the casing head in the same way. The only difference in this form is that the bore 41 of said adapter is of the same diameter throughout its length. This diameter is slightly larger than the diameter of the split ring 15 when said ring is engaging in the groove 16 of the double collar.

Therefore, it will be obvious that when this adapter 40 is used in place of the adapter 30, it is possible to assemble the ring on the collar 17 before the same is lowered within the casing head. In such event, it is not necessary to remove the bolts 20 until such time as it is desired to remove the blowout preventer and gate valve, together with said adapter. This type of adapter 40, eliminates the necessity of separating said adapter from the base member 10 to permit insertion of the split ring 15, but it is noted that due to the increased diameter of its bore a larger safety valve C and blowout preventer D would have to be employed, than in using the same sized adapter 30.

The running in and landing of the inner casing, with the well under control at all times, may however be performed with the use of any one of the two adapters.

In Figures 7 and 8, I have shown a modified form of the invention. In this form the packing gland 25 of the casing head is provided with an upwardly extending nipple 50 which is externally screw-threaded. It will be obvious that this nipple takes the place of the adapter, and the gate valve C is attached thereto. In running the inner casing A, with this particular form, the split ring 15 is omitted by raising the cap 19 from the base member by removing the nuts 21. The inner casing A is then run into the well in the same way as in the other forms. When the double collar 17 on the string A is lowered the proper distance, the cap 18 is raised and the split ring 15 is inserted. The cap is then replaced and the nuts 21 tightened on the bolts 20 to re-assemble the casing head. In this form, it is only necessary to then unscrew the blowout preventer and safety valve whenever desired and the casing head remains in its assembled position at all times.

The provision of the adapters, or of the threaded nipple 50 at the upper end of the gland 25, permits a safety device to be mounted above the casing head during the period when the inner casing string A is being run into the well. As a result the well is under control at all times which eliminates the danger of damage from blowout, or a fire due to escaping gas. It also prevents leakage or waste of the gas pressure.

What I claim and desire to secure by Letters 75 Patent is:

1. A well structure including, a casing head having a lower member adapted to be fastened on a casing and an upper member bolted thereto for rapid separation without rotation, packing between said head members, the upper head member having an upwardly extending annular screw threaded portion and an annular ring recess at the lower end of its bore, the lower member having a ring seat at its top immediately below the recess of the upper member. 5
2. A well structure including, a casing head member having a full size opening for running drilling tools therethrough, a pipe supporting ring seat at the upper end of the head member extending outwardly from the bore of said head, 15 a flanged adapter, mounted on the head member so as to expose the ring seat and screw threaded at its upper end, said adapter having a bore ample to pass well tools therethrough, and a safety device arranged to pass oil tools therethrough and 20 screwed onto the adapter, the adapter being arranged to be separated from the casing head to permit a split pipe-supporting ring to be mounted on the ring seat. 25
3. The combination of a blowout preventer, a gate valve, a casing head, and an adapter having an outwardly directed flange, the casing having an annular ring seat directed outwardly from its bore for receiving a split pipe-supporting ring, 30 the preventer, gate valve, head and adapter each having a bore ample to pass drilling tools therethrough, means for fastening the adapter to the casing head by the flange of said adapter, the gate valve being mounted on the adapter so as to be in proximity to the casing head and the blowout preventer being mounted on the valve, the elements being readily separable without rotation for upward movement of the adapter, valve and preventer, whereby the ring seat of the head is 35 exposed for the rapid mounting of a pipe-supporting ring and the subsequent lowering and securing of the elements, and packing between the separable elements to form a fluid-tight joint. 40
4. A well structure including, a casing head member adapted to be fastened on a casing and having a ring seat at its top extending outwardly from its bore, an annular adapter having a base flange mounted on the member, packing between the member and the adapter, bolts connecting the member and the adapter flange providing for quick separation without rotation, the adapter having a recess at the bottom of its bore overhanging the ring seat for receiving a pipe supporting ring and also having screw threads at its 50 upper end for attaching a safety device thereon. 55
5. A well structure including, a casing head member adapted to be fastened on a casing and having a ring seat at its top extending outwardly from its bore, a cap member having a base flange 60 mounted on the head member; packing between the members, bolts connecting the head member and the base flange of the cap member providing for quick separation without rotation, the cap member having a recess overhanging the ring seat of the head member for receiving a pipe-supporting ring and also having a packing around its bore, an annular adapter having its lower end engaging the packing of the cap and provided with screw threads on its upper portion, an annular exterior flange intermediate the top and bottom of the adapter, and bolts for securing said flange to the cap member. 65 70 75
